UNITED STATES PATENT OFFICE.

ALBERT DU BRUL, OF NEW YORK, N. Y., ASSIGNOR TO THE MILLER, DU BRUL & PETERS MANUFACTURING COMPANY, OF CINCINNATI, OHIO.

CIGAR-BUNCHING-MACHINE FILLER-FEEDING DEVICE.

SPECIFICATION forming part of Letters Patent No. 636,961, dated November 14, 1899.

Application filed April 4, 1898. Serial No. 676,414. (No model.)

To all whom it may concern:

Be it known that I, ALBERT DU BRUL, a citizen of the United States, and a resident of New York, in the county of New York and State of 5 New York, have invented certain new and useful Improvements in Cigar-Bunching-Machine Filler-Feeding Devices, of which the following is a specification.

My invention relates to an improved feeding apparatus for cigar-making machines in which the tobacco is supplied, preferably in scrap form, to a hopper, from which it supplies a measuring device which sizes the bunches.

15 The object of my invention is to provide means whereby the tobacco may be pushed into the measuring device, so as to fill the opening formed in the latter.

My invention consists, first, in the provision 20 of a plunger or rammer which is mounted on the inside of the hopper and operated in such a manner as to cause its head to reciprocate over the opening of the said measuring device, as hereinafter described and claimed.

25 My invention consists, further, in certain means employed for operating the plunger or rammer, as hereinafter described and claimed.

In order that my invention may be fully 30 understood, I will proceed to describe it with reference to the accompanying drawings, in which—

Figure I is a top view of a filler-feeding device and adjacent parts of a cigar-bunching machine, showing my improvement, the outer plunger being omitted. Fig. II is a vertical section thereof on the line II II of Fig. I, the outer plunger being shown. Fig. III is a vertical section adjacent to the inner 35 plunger or rammer, showing the latter in elevated position. Fig. IV is a vertical section adjacent to the inner plunger or rammer, showing the latter in its lowered position.

1 is a portion of the body of the frame; 2 45 is the rolling-apron; 3 is the follower; 4 is the apron-arm; 5 is the roller-arm; 6 is the outer plunger; 7 is the hopper; 8 is the measuring device or slide, having an opening 8^a; 9 is the crank-lever; 10 is the link connecting the 50 crank-lever with measuring device or slide; 11 is the oscillating shaft, having the operat-

ing crank-arm 12, and 13 is the shaker-plate, secured to the oscillating shaft within the hopper, all of approved construction and forming parts of a cigar-bunching machine of well-known construction. 55

I will now describe my improvement, which is located within and to one side of the hopper.

11^a is an extension to the oscillating shaft. 60 Mounted on and fixed to this extension so as oscillate therewith is a sleeve 14, having a lateral arm 15. Secured to the inside of the hopper is a hollow post or standard 16, having an arm 16^a and a vertical slot 16^b. Adapted 65 to reciprocate within this hollow post or standard is the rod 17 of an inner plunger or rammer, formed with a recessed lower end 17^a, to which is adjustably secured by suitable set-screws 18 and washers 19 a skeleton frame 70 20, providing a plunger-head which is operated over the opening of the measuring device. For reciprocating the inner plunger or rammer I provide the means now described.

21 is a link working in front of the vertical 75 slot on the inner face of the post or standard and connected to the plunger or rammer rod by a screw-pin 22.

23 is a bell-crank lever, pivoted by a screw-pin 24 at its elbow to the post-arm. The upper arm of this bell-crank lever is pivoted by a screw-pin 25 to the upper end of the link, while its lower arm has pivoted thereto by a screw-pin 26 a connecting-arm 27, which in turn is pivoted by a screw-pin 28 to the head 85 29^a of a rod 29, sliding freely in the lateral arm of the vertical sleeve of the oscillating shaft. The sleeve is secured by a cap-piece 30, screw-threaded to the upper end of the extension of the oscillating shaft. By these 90 means when the shaft is oscillated the inner plunger or rammer is caused to reciprocate over the opening in the measuring device and push the tobacco thereinto, while the shaker-plate vibrates on opposite sides of the plunger-head or rammer-head. 95

Having thus described my invention, the following is what I claim as new therein and desire to secure by Letters Patent:

1. A cigar-bunching-machine filler-feeding 100 device comprising a hopper, an oscillating shaft having an extension provided with a

lateral arm, a measuring device having an opening, a reciprocating plunger or rammer, located inside of the hopper, for pushing the tobacco into the opening of the measuring device; and means whereby the plunger or rammer is operated from the lateral arm substantially as described.

2. A cigar-bunching-machine filler-feeding device comprising a hopper, an oscillating shaft having an extension provided with a lateral arm, a shaker-plate fixed to the oscillating shaft, within the hopper, a measuring device having an opening, a plunger or rammer located inside the hopper, and means operated by the lateral arm for causing the plunger or rammer to reciprocate over the measuring device for pushing the tobacco into the opening of the latter; substantially as described.

3. A cigar-bunching-machine filler-feeding

device comprising a hopper having a discharge-opening, an oscillating shaft having an extension provided with a lateral arm, a hollow post or standard having an arm and a vertical slot and secured to the hopper, the plunger or rammer having a rod adapted to slide in the hollow post or standard, and a head adapted to be reciprocated over the discharge-opening, the slide or link connected with the plunger or rammer rod through the slot, the pin having a head and loosely mounted in the lateral arm, the connecting-arm pivoted to the pin-head, and the bell-crank lever pivoted to the post-arm and pivotally connecting the link with the connecting-arm; substantially as described.

ALBERT DU BRUL.
